UNITED STATES PATENT OFFICE.

STEPHEN SHELLHAMMER, OF WOODLAND, CALIFORNIA.

ICE-CREAM-CONE HOLDER.

1,067,151.

Specification of Letters Patent.

Patented July 8, 1913.

Application filed January 25, 1913. Serial No. 744,134.

To all whom it may concern:

Be it known that I, STEPHEN SHELLHAMMER, a citizen of the United States, residing at Woodland, in the county of Yolo 5 and State of California, have invented a new and useful Ice-Cream-Cone Holder; and I do hereby declare the following to be a full, clear, and exact description of the invention, such as will enable others skilled 10 in the art to which it appertains to make and use the same.

This invention relates to a new and useful ice-cream cone holder.

As an object of the invention, it is the 15 aim to construct of a single length of wire material, a skeleton frame having a plurality of coils or loops constituting holders for ice-cream cones, and provided with supporting legs and a suitable handle.

20 The invention comprises further features and combination of parts, as hereinafter set forth, shown in the drawings and claimed.

In the drawings:—Figure 1 is a view in 25 perspective of the improved ice-cream cone holder constructed of a single length of wire material, showing two cones supported thereby. Fig. 2 is a plan view of the holder.

Referring more particularly to the drawings 1 designates a single length of wire material, looped upon itself substantially at 30 its central portion to form a coil 2 to receive an ice-cream cone. The wire material immediately adjacent the coil 2 or loop is 35 twisted together as indicated at 3. Beyond the twisted portion 3, the wire material extends laterally in opposite directions forming the portions 4. Each portion 4 is formed in a twisted leg terminating at its 40 lower end in a loop 6, constituting a foot, and said legs are denoted by the numeral 5. Adjacent said legs 5, the wire material is 45 formed into coiled loops 7 adapted to hold cones. The wire material forward of the coils 7 is constructed into coiled loops 8 to 50 also support cones. The wire material is twisted together adjacent the coiled loops 8 to form additional legs 9 having loops 10 at their lower ends forming feet. Beyond the legs 9, the wire material of each side of the holder is brought to substantially a pointed portion and twisted together as indicated at 55 11, immediately adjacent which twisted portion 11 an annular loop forming a cone

holder 12 is constructed. Close to the holder 55 12, the wire material is again twisted at 13, and beyond which twist 13, the two portions 14 of the wire material are spread apart, extended rearwardly and coiled about the lateral portions 4, as indicated at 15. The 60 two portions 14 constitute reinforcing or bracing rods or members, between the loop or holder 12 and the portions 4. The two portions 14 not only brace the loop or holder 12 and the portions 4, but together with the 65 loop 12 (which as will be seen connects with the other structure), insure rigidity and strength for the entire ice-cream cone holder. Beyond the coils 15 the wire material is again twisted together as shown at 70 16, while the end portions of the wire material are twisted together as illustrated at 17, thereby forming a looped handle 18.

From the foregoing it is to be ascertained that there has been devised a novel, yet exceedingly simple structural skeleton frame constituting an ice-cream holder with a plurality of coiled loops to receive cones, and all of which parts are constructed of a single length of wire material, it having been 80 found that such a holder is extremely desirable and practicable.

The contour of the single wire constructed 85 ice-cream cone holder substantially resembles the shape of a heart.

The invention having been set forth, what is claimed as new and useful is:—

1. A substantially heart-shaped ice-cream cone holder constructed of a single length of wire material and provided with a plurality of coiled loops to receive cones, said wire material being twisted together to form legs, and constructed to form centrally arranged brace rods for the holder, said brace rods terminating together to form a looped handle.

2. In combination, a single length of wire material coiled upon itself at its central portion to form a loop to receive a cone, said wire material beyond said loop arranged in a contour substantially resembling the shape of a heart, thereby providing a frame having coiled loops and supporting legs, the wire material adjacent the pointed portion of the heart-shaped frame extending inwardly thereof and twisted together to form an additional cone holding loop, said wire material beyond this additional loop con-

stituting reinforcing rods coiled about that portion of the heart-shaped frame opposite the pointed portion, and beyond said reinforcing rods the wire material is constructed 5 and twisted together to form a looped handle.

In testimony whereof I have signed my

name to this specification in the presence of two subscribing witnesses.

STEPHEN SHELLHAMMER.
